UNITED STATES PATENT OFFICE.

CHARLES E. MURRAY, OF BRANDT, OHIO.

SASH-HOLDER.

SPECIFICATION forming part of Letters Patent No. 292,442, dated January 22, 1884.

Application filed October 31, 1883. (No model.)

To all whom it may concern:

Be it known that I, CHARLES E. MURRAY, a citizen of the United States, and a resident of Brandt, in the county of Miami and State 5 of Ohio, have invented certain new and useful Improvements in Window-Springs; and I do hereby declare that the following is a full, clear, and exact description of the invention, which will enable others skilled in the art to 10 to which it appertains to make and use the same, reference being had to the accompanying drawings, which form a part of this specification, and in which—

Figure 1 is a vertical sectional view of a portion 15 of a window frame and sash provided with my improved spring. Fig. 2 is a perspective view of a portion of the sash and the spring, and Fig. 3 is a detail view of the spring detached.

Similar letters of reference indicate corresponding parts in all the figures.

My invention has relation to springs secured upon the frame or sash of a window, serving to hold the sash raised by the friction 25 between that edge of the sash opposite to the spring and the way in which that side of the sash slides; and it consists in the improved construction and combination of parts of a double spiral spring adapted to be secured in 30 a recess in the frame of sash of the window, and to bear against the opposite way or surface, the spring being so constructed that only one-half of the tension of the spring has to be overcome in raising or lowering the sash, as 35 hereinafter more fully described and claimed.

In the accompanying drawings, the letter A indicates the window-frame, B the sash, and

C a recess in the edge of the said sash, in which the spring D is secured. The spring consists of one piece of wire consisting of a 40 central straight piece, E, bent at its ends to form two spirals, F, coiled in opposite directions, and the ends of these spirals are passed in opposite directions, as shown at G, parallel, or nearly so, with the straight piece, and bent 45 at their outer ends, H, which are inserted into the bottom of the recess. It will be seen that both spirals will serve to force the straight central portion of the spring out against the opposite surface, against which it will bind by 50 friction and hold the sash, and it will also be seen that in raising or lowering the sash the portion of the spring facing toward the direction of the motion will be compressed, allowing the sash to move, forming less resistance 55 than the entire spring.

Having thus described my invention, I claim and desire to secure by Letters Patent of the United States—

The combination of the frame of a window, 60 the sash having a recess in its edge, and a spring consisting of a straight portion, having its ends coiled in opposite directions, the ends of which coils are passed back in opposite directions and secured in the bottom of the recess, as and for the purpose shown and set forth.

In testimony that I claim the foregoing as my own I have hereunto affixed my signature in presence of two witnesses.

CHARLES E. MURRAY.
